UNITED STATES PATENT OFFICE.

HENRY R. ASTRIDGE, OF TORONTO, ONTARIO, CANADA.

DISAPPEARING PROPELLER DEVICE.

Application filed April 13, 1922. Serial No. 552,330.

To all whom it may concern:

Be it known that I, HENRY R. ASTRIDGE, of the city of Toronto, in the county of York, Province of Ontario, Canada, a subject of the King of Great Britain, have invented certain new and useful Improvements in Disappearing Propeller Devices, of which the following is a specification.

This invention relates to devices such as shown and described in United States Letters Patent No. 1,225,252, of May 8th, 1917.

In this device a casing is provided open at its under side and adapted to receive and house a propeller and propeller shaft. A motor crank shaft is journaled in one end of the casing, and the propeller shaft is connected thereto by means of a universal joint. Extending through the sides of the casing is a short rock shaft to which, within the casing, is secured a propeller shaft support having a sliding engagement with the propeller shaft.

The propeller shaft is raised and lowered by the oscillation of the rock shaft.

The tendency is, when the boat is running, for the propeller and propeller shaft to lift, and means must therefore be provided to hold them down, but such means must not interfere with the movement of the parts when the skeg of the propeller shaft supporting device strikes an obstruction tending to lift it. My object therefore is to devise simple, effective and easily adjustable means for actuating the propeller supporting device and for frictionally retaining it in any desired position.

I attain my object by means of the constructions hereinafter described and illustrated in the accompanying drawings in which—

Fig. 1 is a side elevation, partly in section, of a motor attachment constructed in accordance with my invention:

Fig. 2 is a side elevation on a larger scale of part of the same showing particularly the frictional retaining means for the hand lever; and

Fig. 3 a cross section of these parts on the same scale.

In the drawings like numerals of reference indicate corresponding parts in the different figures.

1 is a casing of the device open at its under side and adapted to receive the propeller shaft 2 and propeller 3. The crank

shaft 4 of the motor extends through the forward end of the casing 1, which is provided with a suitable stuffing box 5. Within the casing, the crank shaft is connected to the propeller shaft by means of a universal joint 6. The propeller shaft is carried, so that it may be raised or lowered, by the propeller shaft support 7. This shaft support is pivotally supported within the casing by means of the rock shaft 8 hereinafter more particularly described. The rearward end of the support carries a suitable bearing 9 for the propeller shaft. Preferably the support 7 is double, passing on each side of the propeller shaft, and the bearing 9 is hung on a pivot 10 between the two parts of the support. The bearing turns on this pivot as the propeller shaft is raised or lowered, and at the same time slides longitudinally of the shaft.

At the junction of the two parts of the support 7 an open bearing 11 is formed, which receives the propeller shaft when the latter is in its lowest position.

To protect the propeller I provide the skeg 12 which extends rearwardly from the support 7 below the bearing 11.

The rock shaft 8, it will be noted, extends through openings in the opposite sides of the casing 1, which openings are surrounded by the stuffing boxes 13 and 14, the sides of the casing forming the bottoms of these boxes. One end of the rock shaft is provided with an enlargement 15, preferably integral with the shaft, which forms a gland for the stuffing box 13. The stuffing box 14 is provided with a gland 16, which is adapted to be set up by a nut 17 threaded on the end 18 of the rock shaft. The center 19 of the rock shaft, it will be seen, is squared or otherwise shaped to have a non-rotative engagement with the propeller shaft support 7 and, as the end 18 of the rock shaft is smaller than this squared portion of the shaft, the rock shaft is readily engaged with the said support by pushing it through the latter from left to right, as viewed in Fig. 3, by setting up the nut 17 without producing undue strain against the sides of the casing. To the end 15 of the rock shaft I secure a brake drum 20, preferably connection is effected by means of a cap screw 21, passing through the end of the drum and threaded in the enlarged end 15 of the rock shaft.

One or more dowels 22, fitting in alined holes in both the end of the drum and the end of the rock shaft, prevent rotary movement of the drum relative to the rock shaft.

5 On the sides of the casing adjacent the drum, and preferably diametrically opposite one another, are formed the lugs 23. To one of these lugs are secured the ends of the halves 24 of a brake band 31, preferably by 10 means of a bolt 25 extending through the lug and the ends of the brake band. Through the other lug and the other ends of the halves of the brake band extends the bolt 26. One end of this is provided with a wing 15 nut 27 whereby the bolt may be caused to tighten the brake band upon the drum to any extent desired. The other end of the bolt has a cam lever 28 pivoted thereon, which is operable to quickly release the pressure of the brake band whenever desired. 20 An operating handle 29 is secured to the end of the brake drum, preferably by means of the cap screw 21, which secures the brake drum to the rock shaft. This operating 25 handle or lever is fitted between the lugs 30 formed on the brake drum, which thus prevent relative rotation of the handle of the drum.

It is evident that the rock shaft may be 30 actuated by means of this handle to throw the propeller shaft up or down, as desired. When the propeller shaft is down, it may be held down against any normal upward pressure by suitably tightening the wing nut 35 27. As only frictional resistance is opposed to the upward movement of the propeller shaft support and propeller, the support is readily pushed up by contact of the skeg of the shaft support with an obstruction. To 40 facilitate the raising of the propeller shaft by means of the operating handle 29, the cam lever 28 may be pulled up and the pressure of the brake band thus released.

What I claim as my invention is:—

45 1. In a motor attachment for boats, the combination of a casing open at its underside and adapted to receive and house a propeller and propeller shaft; a propeller shaft and a propeller adapted to be raised and 50 lowered; a propeller shaft support adapted to raise and lower the propeller shaft; a rock shaft journalled in the sides of the casing, said shaft being adapted to actuate the propeller shaft support; a friction drum on 55 one end of said rock shaft; and an adjust-

able brake band connected with said casing and engaging said friction drum.

2. In a motor attachment for boats, the combination of a casing open at its underside and adapted to receive and house a propeller and propeller shaft; a propeller shaft and propeller adapted to raise and lower the propeller shaft; a rock shaft journalled in the sides of the casing, said shaft being adapted to actuate the propeller shaft support; a friction drum on one end of said rock shaft; two lugs on said casing at opposite sides of said drum; two half brake bands pivotally connected to one of said lugs; and an adjusting bolt extending through the other lug and the other ends of said brake band.

3. In a motor attachment for boats, the combination of a casing open at its underside and adapted to receive and house a propeller and propeller shaft; a propeller shaft and propeller adapted to be raised and lowered; a propeller shaft support adapted to raise and lower the propeller shaft; a rock shaft journalled in the sides of the casing, 60 said shaft being adapted to actuate the propeller shaft support; a stuffing box formed at each side of the casing through which said shaft passes; a fixed gland formed at one end of the rock shaft co-operating with 65 one stuffing box; an adjustable gland for the other stuffing box carried by the shaft; a friction drum secured to the end of the shaft formed with the fixed gland; and an adjustable brake band connected with said casing 70 and engaging said friction drum.

4. In a motor attachment for boats, the combination of a casing open at its underside and adapted to receive and house a propeller and propeller shaft; a propeller shaft and propeller adapted to raise and lower the propeller shaft; a rock shaft journalled in the sides of the casing, said shaft being adapted to actuate the propeller shaft support; a friction drum on one end of said rock shaft; two lugs on said casing at opposite sides of said drum; two half brake bands pivotally connected to one of said lugs; and an adjusting bolt extending through the other lug and the other ends of said brake band, 80 said bolt being provided with nut at one end and a cam lever at the other.

Signed at Toronto, Canada, this 7th day of March, 1922.

HENRY R. ASTRIDGE.
